UNITED STATES PATENT OFFICE.

ROY A. FRY, OF OMAHA, NEBRASKA.

RAILWAY-SIGNAL.

1,323,974.

Specification of Letters Patent.

Patented Dec. 2, 1919.

Application filed May 28, 1917. Serial No. 171,462.

To all whom it may concern:

Be it known that I, ROY A. FRY, a citizen of the United States, residing at Omaha, in the county of Douglas and State of Nebraska, have invented certain new and useful Improvements in Railway-Signals, of which the following is a specification.

The invention relates to railway signals and particularly to circuit controlling devices operable by the depression of the rail. Such devices are commonly used to control crossing warning signals and the like, and the invention will be described as so applied, without, however, implying necessary limitations to this field.

The invention provides a simple and reliable circuit controlling device operable by minute depressions of the rail, but not injuriously affected by larger depressions, so that it will operate with certainty under varying conditions of the track and regardless of the speed of the train. The force exerted upon the circuit controlling mechanism is varied little if at all by the extent or rapidity of depression of the rail, and the device adjusts itself automatically to proper relation with the rail so as always to be in operative condition. By simple alterations in assembly it may be adapted for open circuit or closed circuit systems.

In the accompanying drawings I illustrate a preferred embodiment of the invention, in which:

Figure 1 is a longitudinal vertical section of an instrument embodying my invention, the casing being shown partly in elevation;

Fig. 2 is a horizontal section of the same on the line 2—2 of Fig. 1;

Figs. 3 and 4 are detail side views of the circuit-controlling devices, representing the parts in different positions assumed during operation;

Fig. 5 is a detail side view of a part of the rail-actuated plunger, showing the frictional clutch-sleeve thereon;

Fig. 6 is a detail horizontal section on the plane of the line 6—6 of Fig. 5;

Fig. 7 is a detail side view of the circuit-controlling devices as arranged for use on normally-open circuits;

Fig. 8 is a detail plan view of the reversible switch-block showing the means for supporting the same in the casing.

In the illustrated embodiment of my invention there is provided a metal casing 55 of substantially rectangular form, having a side-plate 11 removably secured thereon by screws 12, the edges of the casing adjoining the sideplate having a groove 13 in which suitable packing may be placed to insure a 60 water-tight joint between the parts. When the instrument is in use, the casing is disposed with one end thereof beneath one of the rails A of a railway track, being supported by two metal bars 14 and 15 of 65 which the ends rest upon and are secured to adjoining cross-ties B of the track, as shown in Figs. 1 and 9. The bar 14 is secured to a lug or bracket 16 projecting from the end of the casing, and the bar 15 is secured by a 70 bolt or screw to the top of the casing near the end thereof which extends out laterally from the rail A. In the top of the casing, beneath the rail A, there is a packing-gland 17 which surrounds the upper portion of a 75 vertically disposed plunger 18. The upper end of said plunger engages the lower side of the rail and is held in engagement therewith by means of a coil spring 19 which is disposed around the lower end-portion of 80 the plunger and extends down into a pocket 20 at the lower side of the casing. The middle portion of the plunger is larger in diameter than the end-portions thereof, and said larger middle portion forms shoulders 85 one of which serves as a limit stop for the upward movement of the plunger, and the other of which is engaged by spring 19. By the described arrangement of parts, vertical 90 movements of the rail A relative to the ties B, during the passage of trains along the track, cause reciprocating movements of the plunger relatively to the casing, and such movements of the plunger are employed to actuate the circuit-controlling mechanism. 95

On the larger cylindrical portion of the plunger within the casing, there is disposed a frictional clutch-sleeve comprising two parts 21 and 22 fitting upon opposite sides of the plunger as best shown in Figs. 5 and 100 6. At the sides of said sleeve-parts 21 and 22 there are pairs of perforate lugs, those on the part 21 being threaded to receive the ends of screws 23. These screws pass freely through the openings in the lugs on the part 22. Coil springs 24 are mounted upon

the screws between the heads thereof and the lugs on the part 22, and being held in compression by the screws, serve to press the sleeve parts into frictional engagement 5 with the plunger. The frictional pressure is varied by adjusting the screws 23.

At opposite sides of the clutch-sleeve are trunnions or lugs 25. The latter are journaled in bearings in a lever 26 formed of 10 two flat bars which are spaced apart at one end so as to straddle the clutch-sleeve, the lever extending horizontally therefrom toward the other end of the casing. Near the free end of the lever the side-bars thereof 15 are secured together by a rivet 27, and the spaced portions adjacent to the clutch-sleeve are connected by a cross-bolt 28. The spaced portions of the lever extend slightly beyond the clutch-sleeve and are pivoted on a ful- 20 crum-pin 29 which extends transversely between the back of the casing and a lug 30 depending from the upper side of the casing adjacent to the removable side-plate 11. The free or movable end of the lever 26 extends 25 between upper and lower stop-pins 31 and 32 which project from the back of the casing toward the side plate 11, and adjacent to said pins there is a lug 33 which extends from the back of the casing to the side of the 30 lever and prevents lateral movement thereof.

From the described arrangement of the clutch-sleeve and lever, it results that very slight vertical reciprocating movements of the plunger will cause movements of the lever 26 between the stop-pins 31 and 32, and such movements of the lever may be utilized for actuating or controlling signals or electrical circuit-controlling devices. Any movement of the plunger greater than that 35 necessary to actuate the lever between the described limits of movement will merely cause slipping of the plunger through the frictional clutch-sleeve, the lever being held in engagement with the stop-pin toward 40 which it was last moved, and moving toward the other stop-pin when the plunger commences movement in the opposite direction. After the instrument is once installed it will remain automatically in operative 45 condition, regardless of variation of the relative positions of the rail A and ties B within the limits of slip of the clutch. Thus if the rail should assume a position lower than it occupied when the instrument was in- 50 stalled, the plunger would be merely pushed further down through the clutch-sleeve, while if the rail should be raised relatively to the ties, the plunger would follow it up so as to remain in engagement with it, the 55 spring 19 pushing the plunger through the clutch to the new position. Obviously, the adjustment of the clutch-pressure must be such that the plunger can be moved through the sleeve by the pressure of the spring 19 as

well as by the downward pressure of the 65 rail, and the friction between the clutch-sleeve and plunger must be sufficient to actuate the lever 26 and the signal or circuit-controlling devices connected therewith. Under conditions of service, regardless of what 70 the normal relative positions of the rail and ties may be, the movement of a train, engine or car along the track will disturb the normal condition and change the relative positions of the rail and ties enough to cause 75 vertical movements of the plunger sufficient in extent to actuate the lever and cause oscillatory movements thereof between the stop-pins 31 and 32.

The preferred means for utilizing the de- 80 scribed oscillatory movement of the lever 26 are as follows: On the movable end of the lever, or that end opposite the end fulcrumed on the pin 29, there are pivoted two approximately L-shaped pawls, having 85 downwardly extending fingers 34 and 35, and fingers 36 and 37 extending back alongside the lever past the stop-pins 31 and 32 and adjacent respectively to the upper and lower edges of the lever. The depending 90 fingers 34 and 35 diverge from their common pivotal axis, and the lower ends thereof are connected to each other by a small coil spring 38, as shown in Figs. 3 and 4.

Said depending fingers of the pawls pass 95 on opposite sides of a small horizontal shaft 39, of which the one end is supported in a lug at the back of the casing, and the other end is carried by a lug 40 extending up from the bottom of the casing adjoining the side- 100 plate 11. To said shaft 39 there are pivotally connected two weighted arms 41 and 42, each having a flat portion which extends above the shaft, and an upwardly inclined portion which carries at its end the weight 105 or hammer 43. On the lower side of each arm, near the pivoted end thereof, a flat spring 44 is secured thereto and extends out horizontally beneath the upwardly inclined portion, the free end of the spring resting 110 on a lug 45 extending up from the bottom of the casing, and the spring thus forming a yieldable support for the respective hammer. The arms 41 and 42 have laterally offset 115 portions at their adjacent sides above the shaft 39, and the pawl-fingers 34 and 35 extend adjacent to opposite sides of the respective offset portions, the spring 38 tending to pull the fingers into engagement therewith. Pointed lugs 46 and 47 are provided on the 120 respective fingers 34 and 35, the lug 46 being beveled at its lower edge, and the lug 47 being beveled at its upper edge. The lug 47 is so arranged that when the lever 26 is raised against the stop-pin 31, as shown in Fig. 3, said lug will pass in above the end of the arm 42, and engage over the same. As the lever 26 swings upward, finger 36 en-

counters stop-pin 31, causing finger 34 to swing outward or away from the edge of the offset of plate 44, so that lug 46 may not engage with said plate even if the plate swing 5 above said lug.

Upon downward movement of the lever 26 from said upper position, the arm 42 is swung upwardly as shown by dotted lines in Fig. 3, and as the lever approaches the stop-pin 32, the finger 37 engages said stop-pin and moves the finger 35 so that the lug 46 is disengaged from the arm, thereby permitting the arm to drop back toward its normal or initial position. Similarly, when the lever 26 is in the lower position at which it engages the stop-pin 32, the lug 46 passes in beneath the offset part of the arm 41, and upon upward movement of the lever said arm 41 is raised until the finger 36 engages 20 the stop-pin 31 and disengages the lug from said arm, thereby permitting the arm to drop. The weights or hammers 43 are so proportioned to the strength of the spring 44 that as each is dropped from such a position as that shown by dotted lines in Fig. 3 it will pass momentarily beyond the normal position to a position such as that shown by dotted lines in Fig. 4, the spring 44 being bent but immediately raising the hammer 30 to its normal position. As the hammers 43 are raised to substantially uniform heights, regardless of the rate of operation of the mechanism, it will be obvious that the force or momentum of the hammers in dropping 35 will also be substantially uniform, and that the electrical circuit-controlling devices actuated by the dropping of the hammers will thus be protected against excessive or injurious force.

In the illustrated form of the circuit-controlling devices there is provided a rectangular block 48 of insulating material which is arranged in the casing adjacent to the hammers 43. The insulating block is held in position by means of a stud 49, which projects from the back of the casing through an opening in the block, and has a nut 50 screwed on the end thereof adjacent to the side-plate 11. There are also two dowel-pins 51 which project from the back of the casing into openings in the block 48, said pins being shorter than the stud 49, but the openings therefor extending entirely through the block so that the pins may enter either 55 side thereof. On the block 48 are mounted two switches, each comprising a contact-plate 52 secured to the block by a screw 53, and a contact-spring 54 secured to the block by a screw 55. Both the plates and springs 60 extend beyond the end of the block, the projecting portions being convergent, and the springs extending beyond the ends of the plates and terminating beneath the hammers 43. In the arrangement of the parts shown

in Figs. 1 to 4, inclusive, the plates 52 are disposed on the upper side of the switch-block 48, the springs 54 are disposed on the lower side of the block, and the upper sides of the springs are normally in contact with the ends of the plates. With this arrangement, the hammers 43 strike the contact-springs when at the lower position shown by dotted lines in Fig. 4, depressing the springs sufficiently to disengage them from the ends of the plates 52, and thus opening 70 any electrical circuit normally closed by the engagement of said members. The two switches formed by the plates 52 and springs 54 are connected in series, one of the line wires 56 being connected with the screw 53 of one switch, the screw 55 of said switch being connected by a wire 57 with the screw 53 of the other switch, and the screw 55 of the latter switch being connected with the other line-wire. The line-wires 56 are 85 brought into the casing through a pipe or conduit 58 entering the end thereof through a packing-gland 59, as shown. The switches being in series, it is obvious that the circuit may be broken by the dropping of either 90 of the hammers 43 onto the contact-spring of its respective switch.

In the arrangement of the circuit-controlling devices shown in Figs. 7 and 8, the contact-springs 54' are disposed on the upper side of the switch-block, the contact-plates 52' are disposed on the lower side of the switch-block, and the projecting portions of the plates and springs are so arranged that they are not normally in contact with each other. The two switches are connected in parallel, the screws 53' being connected electrically by a wire 60, and the screws 55' being connected electrically by a wire 61, while the line-wires are connected one to one of the screws 53' and the other to one of the screws 55'. Dropping of the hammers 43 causes the springs 54' to be pressed into engagement with the ends of the plates 52', thus closing the circuit through the line-wires by the operation of either switch. It will be obvious that by reversing the position of the switch-block on the stud 49 and pins 51, slightly spreading apart the projecting portions of the contact-plates and springs, and changing the cross-connection of the switches from series to parallel, the closed-circuit instrument may be readily changed to an open-circuit instrument. Similarly, an open-circuit instrument may be converted into a closed-circuit instrument by bending the springs to contact normally with the plates and changing from parallel to series connection. The line-wire circuit may include any usual signal device.

It will be observed that under the described construction the rail does not act directly upon lever 26, but upon the recip-

rocating plunger 18, which transmits motion to lever 26 through the friction clutch or connection described. The friction clutch is located close to the fulcrum of lever 26 where the lever is firmly supported, and consequently when the movements of said lever are arrested by the stop-pin 31 or 32, the plunger may be forced to slide through the friction clutch without danger of injury to or distortion of the lever, even though very considerable friction be applied to the plunger. This arrangement is advantageous because there is always an excess of force available to move the plunger, and hence it is practicable, as it is also desirable, to apply a heavy friction so as to insure a strong movement of lever 26 such as will cause a proper actuation of the hammers 43 or other operated device. The free end or long arm of lever 26 has comparatively little work to perform, but owing to its length, resistance to movement of the lever acting at the outer or free end thereof, necessitates application of considerable energy to said lever near its fulcrum, and this in turn makes necessary the relatively strong frictional connection through the clutch device.

From the foregoing the structure, operation and utility of my track-instrument will be clearly understood, and it will be obvious to those skilled in the art that the illustrated and described structure may be extensively modified and rearranged without departing from the spirit of the invention disclosed.

Having now described my invention, what I claim is:—

1. In a track instrument for railway signals, the combination of a reciprocating member adapted to be actuated directly by the rail; a lever; a slipping clutch interposed between said member and a point on the lever closely adjacent the fulcrum of the latter; means for limiting the movement of said lever; and signal controlling means connected with said lever at a point remote from its fulcrum.

2. In a track instrument for railway signals, the combination of a support adapted to have a fixed relation to the ties of a railway track; a lever fulcrumed on said support; stops limiting the movement of said lever on its fulcrum; a reciprocating member adapted directly to engage and be actuated by the rail, to partake of the movements of the rail relative to the ties; a slipping clutch connecting the reciprocating member with the lever at a point close to the fulcrum of the latter; and signal-controlling means, connected with said lever at a point remote from fulcrum thereof.

3. In a track-instrument for railway signals, a reciprocable member to bear against and be directly actuated by a rail, a lever,

stops limiting the movements of said lever, 65 a frictional clutch connecting the reciprocable member and the lever and serving to transmit motion from the former to the latter, and signal-controlling means operable by said lever.

4. In a track instrument for railway signals, the combination of a rail-actuated plunger; a signal-controlling means including a lever having a restricted movement; and a slip clutch connecting said plunger with said lever at a point close to the fulcrum of the latter.

5. In a track instrument for railway signals, the combination, with a rail and ties of a track, of a rail engaging plunger; tie-supported means for pressing said plunger yieldably toward the rail; a signal-controlling lever; stops limiting the movements of said lever; and frictional connecting means between said plunger and lever at a point 85 near the fulcrum of the latter.

6. In a track-instrument for railway signals, a rail-actuated reciprocating member, a pivotally mounted weighted arm, a pawl carried by said reciprocating member and engageable with said arm to lift the same, means for disengaging the pawl from the arm at a predetermined point to drop the latter, and signal-controlling means actuated by the dropping of said arm.

7. In a track-instrument for railway signals, signal-controlling means including a yieldable member, a weight yieldably supported adjacent to said member, rail-actuated means for lifting said weight, and means for 100 disengaging the lifting means from said weight to drop the latter from a predetermined height onto the yieldable member of the signal-controlling means.

8. In a track-instrument for railway signals, a circuit-controlling switch including a yieldable member and a relatively fixed member, a block on which said switch-members are mounted, rail-actuated means for engaging said yieldable switch-member, and means for supporting said block adjacent to said rail-actuated means in either of two reverse positions in which the yieldable switch-member when engaged by the rail-actuated means is movable, respectively, toward and away from the fixed switch member.

9. A track-instrument for railway signals comprising in combination, a rail actuated reciprocating member; a multiplying lever; an impositive connection between said member and lever; a weight guided to move in a fixed path; a pawl carried by said lever and engageable with said weight to lift the latter; means for disengaging said pawl after 120 said weight is lifted, to drop the weight; and signal controlling means operable by the dropping of the weight.

10. A track-instrument for railway signals, comprising in combination, a rail actuated reciprocating member; a multiplying lever; an impositive connection between 5 said member and lever; weights guided to move independently in fixed paths; two pawl mechanisms operatively associated with said lever, one adapted to lift one of said weights upon the downward movement of the lever and the other adapted to lift the other of 10 said weights upon the upward movement of the lever; means for tripping off said pawl mechanisms in the upward positions of said weights; and a signal controlling means operable by the falling of either weight. 15

In testimony whereof I have signed my name to this specification.

ROY A. FRY.
